DESIGN FOR A TOY ANIMAL

Leopold Gottlieb, New York, N. Y.

Application February 3, 1939, Serial No. 82,761

Term of patent 3½ years

To all whom it may concern:

Be it known that I, Leopold Gottlieb, a citizen of the United States, residing at 898 West End Avenue, in the city and county of New York and State of New York, have invented a new, original, and ornamental Design for Toy Animals, of which the following is a specification, reference being had to the accompanying drawing, forming part thereof.

The figure is a perspective view of a toy animal, showing my new design.

I claim:

The ornamental design for a toy animal, as shown.

LEOPOLD GOTTLIEB.
